DESIGN FOR A NUTCRACKER OR SIMILAR
ARTICLE

Kendall Clark, Dayton, and William Merrill Allen,
Hamilton, Ohio, assignors to The W. W. Boes
Company, Dayton, Ohio, a corporation of Ohio

Application June 8, 1946, Serial No. 130,544

Term of patent 7 years

(Cl. D44—1)

To all whom it may concern:

Be it known that we, Kendall Clark and William Merrill Allen, citizens of the United States, residing at Dayton, in the county of Montgomery, and Hamilton, in the county of Butler and State of Ohio, respectively, have invented a new, original, and ornamental Design for a Nutcracker or Similar Article, of which the following is a specification, reference being had to the accompanying drawings, forming a part thereof.

In the accompanying drawings:

Figure 1 is a perspective view of a nutcracker showing our new design;

Figure 2 is a top plan view thereof;

Figure 3 is an end elevation thereof, looking toward the device from the right hand end as seen in Figure 2;

Figure 4 is an end elevation thereof, looking toward the device from the left hand end as seen in Figure 2;

Figure 5 is a side elevation of the device; while

Figure 6 is a view looking toward the underneath surface of the device.

We claim:

The ornamental device for a nutcracker or similar article, substantially as shown.

KENDALL CLARK,
WILLIAM MERRILL ALLEN.
